UNITED STATES PATENT OFFICE.

FRANK W. KELLY AND ALEX H. LUEDICKE, OF MILWAUKEE, WISCONSIN.

HOLDER FOR PASTEURIZING MILK, CREAM, AND OTHER LIQUIDS.

Application filed January 27, 1923. Serial No. 615,404.

To all whom it may concern:

Be it known that we, FRANK W. KELLY and ALEX H. LUEDICKE, citizens of the United States, and residents of Milwaukee, 5 in the county of Milwaukee and State of Wisconsin, have invented new and useful Improvements in Holders for Pasteurizing Milk, Cream, and Other Liquids, of which the following is a description, reference being had to the accompanying drawings, which are a part of this specification.

The invention relates to holders or tanks, and more particularly to holders for pasteurizing milk, cream, and other liquids.

Heretofore, in pasteurizing milk and cream, the holders were formed in units, each unit usually comprising from four to eight holders with but one set of valve operating mechanism for the unit. This 20 system had its disadvantages in that the holders were necessarily limited in size and also only a certain fixed number of holders could be used in each unit. A further disadvantage was that no means was provided for adjusting the temperature in the 25 individual holders.

It is one of the objects of the present invention to eliminate the above-mentioned disadvantages by providing mechanism for 30 holders which will permit the use of an unlimited number of holders and irrespective of the size of the holders.

A further object of the invention is to 35 provide a plurality of mechanically operated holders for pasteurizing liquids in which each holder is independent of the others.

A further object of the invention is to 40 provide holders of the class described which are lined with glass or porcelain, thereby making them sanitary and easy to clean.

A further object of the invention is to 45 provide holders of the class described which are each provided with heating and insulating jackets to adjust or maintain the temperature within the holders.

A further object of the invention is to 50 provide holders of the class described having inlet and outlet pipes in loop form to permit a flow of the liquid in both directions at all times, thereby preventing stagnation of the liquid and consequent lowering of the temperature of the liquid in any part of the pipe.

A further object of the invention is to

provide holders of the class described which are welded and seamless in construction. 55

A further object of the invention is to provide holders of the class described which are of simple construction, are strong and durable, and are well adapted for the purpose described. 60

With the above and other objects in view, the invention consists of the improved holders for pasteurizing milk, cream and other liquids, and their parts and combinations as set forth in the claims, and all equivalents thereof. 65

In the accompanying drawing in which the same reference characters indicate the same parts in all of the views: 70

Fig. 1 is a plan view of the improved holders and mechanism for operating the same;

Fig. 2 is a front view thereof, parts being broken away and parts being shown in section; and 75

Fig. 3 is a cross sectional view of one of the holders illustrating an agitator and the mechanism therefor. 80

Referring now more particularly to the drawings, the numeral 8 represents a plurality of tanks or holders which are circular in cross section and formed of sheets of metal welded together so as to be seamless. The interiors of the holders are preferably 85 lined with glass or porcelain 8' to facilitate the cleaning thereof. The top portions of the holders are provided with man-holes 9 to permit access to the interior of the holders and said man-holes are normally closed by means of suitable covers 10. The exterior and bottoms of the holders are surrounded by heating and insulating jackets 11 spaced so as to leave a chamber 12 between the same and the holder walls. Said chambers 90 are adapted to have a vacuum created therein or to be filled with a fluid, as will be hereinafter explained, for the purpose of maintaining or adjusting the temperatures within the holders. 95

The holders 8 are arranged in two parallel rows and are conveniently spaced from one another. Supports 13 are connected to opposite holders and on said supports two pairs of longitudinally extending channel iron beams 14 are secured. At various intervals on said beams, plates 15 are positioned which have thereon mechanism for 100 105

operating the holder valves which will be more fully explained.

A motor 16 serves as the source of power, and it is in connection with timing gears 17 from which extends a connecting rod 18. The outer end of said connecting rod is secured to a crank 19 which turns a longitudinally extending crank shaft 20. Fixedly mounted on said crank shaft at various intervals are valve operating cams, an inlet valve cam 21 and an outlet valve cam 22 being seated on each of the plates 15 and one pair of inlet and outlet valve operating cams being provided for each holder in use. Said cams operate arms 23, and for briefness, only the arms and connections for one pair of valves will be explained in detail. A main supply pipe 24 leads to the source of supply of the liquid with which the holders are to be filled (not shown) and the same connects with the feed pipes 24' which are in loop formation as shown in Fig. 1. It has been found to be very advantageous to have said feed pipes in loop formation because they will then permit a flow of the liquid in both directions and at all times and thereby prevent stagnation of the liquid and consequent lowering of the temperature of the liquid in any part of the pipe. Branch pipes 25, which are very short in length, lead to each of the holders. Here they are connected with the inlet nozzles 26 and in said nozzles inlet valves 27 are movably located. The outlet openings 28 are located preferably in the bottom portions of the holders, and pipes 29, in loop formation, lead to a container (not shown) which is to receive the liquid after it has been held in the holders.

As appears in Fig. 2, a valve seat 30 is adapted to receive the outlet valve 27', and the opening will be closed thereby. The valve is moved by means of a valve rod 31 which is within the holder and extends longitudinally of the length thereof, projecting out of the top portion. To said rod, a cable 32 is attached which extends over pulleys 33 and 34 secured in the ceiling of the pasteurizing room. The other end of the cable is made fast to an arm 23 so that when cam 22 forces the arm 23 down, the valve 27 will be lifted, while when the arm is up, the valve will be closed. Springs 23' are interposed between seats 15 and arms 23 to normally urge said arms to a raised position. In regard to the inlet valves, the construction is exactly the same, there being a cable connection from the valve rod to the inlet valve arm.

Each holder is surrounded by a circular pipe 35 and said pipes have connected thereto a plurality of spaced pipe connections 36 which communicate with the chambers 12. Connecting pipes 37 lead from the circular pipes to a longitudinally extending main

supply pipe 38, one end of which extends to a pump or tank (not shown) and the other end is plugged, as at 39, and an additional pipe may be attached thereto, if desired, to feed chambers in additional holders. The purpose of the chambers 12 is to facilitate the adjustment or maintenance of certain temperatures within the holders. For this purpose either a vacuum or a fluid can be used to equal advantage. If it is desired to create a vacuum, a pump is connected to the extremity of pipe 38, and the air is removed from the chambers thereby. If it is desired to fill the chambers with a fluid, steam, hot water or hot air may be used and the same is forced through pipe 38 and the connecting pipes and from the various pipe connections into the chambers. It should be noticed, that the pipe connections are designed to throw the fluid directly against the surface of the tank. In that way, the tank is heated and it is not necessary to have the entire chamber filled with the fluid.

For the purpose of circulating and mixing the liquids in the holders, agitators 40 are provided. Said agitators are of the propeller type and are fixedly carried on shafts 41 which are rotatably mounted in a bearing 42 in the interior of the holders, near the bottoms thereof. The shafts project through the holders and outwardly therefrom and their outer extremities have keyed thereto pulley wheels 43. Said pulley wheels are connected by belts 44 with a drive shaft 45 and are driven thereby.

The operation of the device, which is very simple, is as follows: The milk or other liquid, after being heated to the desired temperature, is fed to the various holders through the pipes and connections. As the operation of the inlet cams is timed, the inlet valves will open in a predetermined sequence, the customary arrangement being for the holders to fill, one after the other. The holders are maintained at the pasteurizing, or desired temperature by means of the vacuum or fluid filled chambers and the milk is held in said holders for approximately thirty minutes, more or less, as desired. Then, as the milk has been held in each holder the predetermined period, the outlet cam of each holder opens its valve and the pasteurized milk is exhausted from each holder in the same sequence in which it was fed.

It is obvious that more holders can easily be added. To do so, it is merely necessary to extend the channel-iron beams and provide additional sets of inlet and outlet valve-operating cams. Then, an extension is added to the crank shaft, and the same is done to pipe 38. The end member 46 of the pipes 24' in loop form is removed by means of the elbow joints 47 and extensions are added to the longitudinal members, after which pipe

46 is replaced. Pipes 24' are then coupled with the additional holders by means of branch pipes. A reverse of the described operation will permit holders to be removed.

5 Thus, it will be seen that the system can be easily and quickly enlarged or made smaller by a continuation or removal of some of the parts as shown.

From the foregoing description, it will be 10 seen that the improved holders for pasteurizing milk, cream and other liquids are of very simple construction, and are well adapted for the purpose described.

What is claimed as our invention is:

15 1. A pasteurizing apparatus, comprising a plurality of tanks, and means for each tank operative to fill and empty each tank at predetermined intervals and in a predetermined sequence, said means permitting the adding 20 of additional tanks to the apparatus, said tanks being formed of plates of metal connected together so as to form a seamless weld and lined with material which will facilitate the cleansing thereof.

25 2. A pasteurizing apparatus, comprising one or more jacketed tanks, and means for each tank operative to fill and empty each tank at predetermined intervals and in a predetermined sequence, said means permitting 30 the adding of additional tanks to the apparatus.

3. A pasteurizing apparatus, comprising one or more jacketed tanks and means for each tank operative to fill and empty each 35 tank at predetermined intervals and in a predetermined sequence, said means permitting the adding of additional tanks to the apparatus, and means for agitating the liquid held in said tanks.

40 4. A pasteurizing apparatus, comprising a plurality of tanks, and means for each tank operative to fill and empty each tank at predetermined intervals and in a predetermined sequence, said apparatus being so arranged 45 and constructed that additional tanks may be readily added to or removed from the apparatus.

5. A pasteurizing apparatus, comprising one or more tanks, timed means for filling

each tank, timed means for emptying each 50 tank, said means permitting the adding of additional tanks to the apparatus, and an agitator for the liquid within each tank.

6. A pasteurizing apparatus, comprising one or more tanks, a cam operated intake 55 valve for each tank, a cam operated outlet valve for each tank, said apparatus being constructed so as to permit the increase or decrease in the number of tanks used in the apparatus, and an agitator for the liquid 60 within each tank.

7. A pasteurizing apparatus, comprising one or more tanks, a cam operated intake valve for each tank, a cam operated outlet valve for each tank, means for timing the 65 movements of the valves of each tank, all of said means permitting the increasing or decreasing of the number of tanks used in the apparatus, and an agitator for the liquid 70 within each tank.

8. A pasteurizing apparatus, comprising one or more seamless, welded, metallic tanks, a cam operated intake valve for each tank, a cam operated outlet valve for each tank, means for timing the movements of the 75 valves of each tank, and an agitator for the liquid within each tank, said tanks being lined with a material which will facilitate the cleansing thereof, and said entire apparatus being so arranged and constructed that 80 tanks may be readily added to or taken from the apparatus.

9. A pasteurizing apparatus, comprising a plurality of tanks, feed pipes arranged in loop formation, an inlet valve in each tank 85 and in close connection with said feed pipes, means for each tank to operate said inlet valves and fill each tank at predetermined intervals in a predetermined sequence, and means for each tank operative to empty each 90 tank at predetermined intervals and in a predetermined sequence, all of said means permitting the adding of additional tanks to the apparatus.

In testimony whereof, we affix our signatures.

FRANK W. KELLY.
ALEX H. LUEDICKE.
